Patented May 24, 1927.

UNITED STATES PATENT OFFICE.

OAK LANDAW, OF NAPPANEE, INDIANA.

TABLE TOP.

Application filed June 10, 1925. Serial No. 36,229.

An object of the invention is to provide a metal top for tables, draining boards or the like.

Another object of the invention is to provide a sheet metal table top with a flange that is rigid and easily assembled.

Another object of the invention is to provide a frame which can be expanded by driving in place transverse braces or cleats to take the bulge or bow out of the metal top and to hold it rigid.

A further object is to provide a frame for a metal table of such construction that the side rails or members of which will not buckle to release the pressure on the metal top.

The subject matter of this invention is disclosed in my patent for "metal table top stretcher" patented August 14th 1923, Number 1,464,910, but is not claimed therein, the present application includes only the table top and frame and illustrates, describes and claims novel features over my co-pending application for table tops filed June 26, 1923 Serial Number 722,605.

With the preceding and other objects and advantages in mind the invention consists in the novel combination of elements, constructions and arrangement of parts, operations and specific features to be hereinafter enlarged upon, claimed and illustrated in the accompanying drawing, wherein:

Figure 1 is a bottom plan view of the device.

Fig. 2 is a sectional view on the line 2—2 of Fig. 1.

Figure 3 is a disassembled perspective view of the frame thereof, and

Fig. 4 is a detail sectional view showing the method of attaching a leg to the top.

In the drawings a table top is illustrated, but it is apparent that the invention may be embodied in metal draining boards for sinks, counter trays, meat-display racks and the like.

Numeral 1 indicates a pressed sheet metal table top having the depending sides 2 and the inturned flange 3 forming a channel in which a frame rests.

The frame consists of end strips 4 and sliding strips 5 having sliding engagement through the tongue 6 on the ends of side strips 5 and grooves 7 formed on the inside of the end strips 4.

Transverse expanding cleats or braces 8 are forced between the side strips 5 at suit-

able points and their tongues 9 engage grooves 10 in the side strips 5 to prevent disengagement.

The ends of the end strips 4 are mitered as at 11, for the purpose of removing pressure from the corners of the table top and longitudinal slots 12 are cut in these end strips 4 back from the mitre 11 and cutaway portions or reduced ends 13 are provided whereby pressure is exerted on the end flange 2 of the metal top.

The lower outside edge of the side strips 5 are beveled as shown at 14. This beveled edge 14 is particularly important because without it, if the outside edge of the side strips 5 were left square, the side strips 5 would have a tendency to buckle thereby reducing or removing the pressure from the flange. A longitudinal groove is provided in the face of the members 4 the purpose of which will be described below.

In operation the sheet metal table top is laid face downward on a work bench (not shown on the drawing) and the end strips 4 are put in place. The side strips 5 are then placed with their tongues 6 engaging the grooves 7 and slide to their outer position.

The transverse braces or cleats 8 are next placed on the dotted line positions, as shown in Fig. 1 and driven to the full line position in the same figure. It is, of course, understood that the transverse braces 8 are long enough to exert a considerable pressure when driven into place so that any bulge or bow, which may exist in the sheet metal top will be removed.

The braces 8 are left in position and thus by means of the tongue and groove connections between braces 8 and the side strips 5, and between the side strips 5 and the end strips 4 a rigid and durable frame is provided.

The mitered ends remove the pressure from the corners of the table top and exert it only on the ends and sides, thereby insuring such pressure that will entirely remove any bulge or bow from the table top.

In Fig. 4 the means of attaching a leg to the table top is shown. An angle 16 attached to the leg L by a screw 17 is inserted in the slot 12 the right angle extention of the angle 16 lying in the groove 15.

It is to be understood that only a preferred form of my invention is herein shown and described and that any departure from

the same, such as in shape, size or arrangement of parts may be resorted to without departing from the spirit of my invention or the scope of the subjoined claims.

5 Having thus described my invention, what I claim as new and desire to protect by Letters Patent of the United States is:

1. In combination with a sheet metal table top having a flanged rim, a frame adapted to fit in the flanged rim, said frame comprising slidable side members, end members co-acting with the side members, mitered, slotted and reduced ends on the end members whereby pressure is removed from the corners of the table top and exerted on the central portion of the ends thereof and trans-

- 15

verse braces adapted to be forced between the slidable side members.

2. A device of the character described comprising grooved end members, mitered, slotted and reduced end thereon, slidable grooved side members, tongues on the ends of the side members and adapted to be received in the grooves of the end members, a beveled lower, outer edge on the side members whereby the side members are prevented from buckling and transverse braces adapted to force the side members away from each other, said braces provided with tongued ends adapted to fit in the groove of the side members.

OAK LANDAW.
